UNITED STATES PATENT OFFICE.

WILLIAM A. HARRIS, OF CHICAGO, ILLINOIS, ASSIGNEE, BY MESNE ASSIGNMENTS, TO THE FLINTKOTE COMPANY, OF BOSTON, MASSACHUSETTS, A CORPORATION OF MASSACHUSETTS.

ROOFING ELEMENT.

1,285,147.

Specification of Letters Patent. Patented Nov. 19, 1918.

Application filed August 28, 1915. Serial No. 47,781.

To all whom it may concern:

Be it known that I, WILLIAM A. HARRIS, a citizen of the United States, and a resident of Chicago, in the county of Cook and State 5 of Illinois, have invented certain new and useful Improvements in Roofing Elements, of which the following is a specification.

This invention has relation to roofing elements, preferably made of prepared flexible 10 roofing material adapted to be laid in horizontal overlapping rows to produce the effect of a shingled or tiled roof.

On the drawings,—

Figure 1 illustrates a roofing element, 15 consisting of a shingle strip, embodying the invention, a like strip adjacent thereto being shown in dotted lines.

Fig. 2 illustrates a portion of a roof formed of said strips.

Fig. 3 illustrates roofing elements in the form of individual shingles embodying the invention.

In the laying of roofing elements on the roof in simulation of wooden shingles or 25 slate or other tiles, it is desirable that the exposed portions in each row should be laterally separated, or otherwise a plain surface such as produced by clapboards would result. But, in order to prevent leaks and 30 to increase the fire protection, it is highly desirable that the lateral edges of the covered or concealed portions should be practically contiguous. It is further highly desirable that the elements should be laid so 35 that the cracks between the several elements in each row should be covered to prevent water from soaking or working down through them, as when the shingles, or the shinglelike tabs or projections in the several rows, are all in alinement or registration.

According to my invention, I form the roofing elements with an upper lateral projection on one side, and a lateral recess on 45 the other side. In the particular embodiments illustrated the projection is in width substantially double the distance laterally between the exposed portions of the shingles or the tabs, and the recess being substantially equal to said distance. In laying the elements, the projection on one side of 50 one element projects into the recess on the other side of the next laterally, adjacent element.

The roofing elements may consist of any

suitable fibrous foundation impregnated with asphalt or other waterproofing composition, and coated on one or both faces with a harder pitch, asphalt or other weatherproof compositions. Ordinarily, though not necessarily, the coating may be colored by any suitable pigment, or else crushed mineral may be embedded in the coating while it is soft and plastic. The material is prepared in sheet form, and may be cut into shingles or shingle strips or into other forms of roofing elements by any suitable machinery.

Referring to Fig. 1, a shingle strip 10 is shown, having any desired number of tabs 11 or projections 11 of any suitable configuration, separated laterally by spaces 12. These tabs or projections constitute the portions of the strips which are exposed when the latter are laid in horizontal overlapping rows. The upper portion of the strip, which is covered or concealed when the strips are laid, is provided on one side with a projection 13, which it will be noted is substantially double, in width, the distance between the tabs or projections 11. On the other side, there is a corresponding recess 14, which however in width is substantially equal to the distance between two adjacent tabs. When two shingle strips are placed side by side, as indicated by the dotted lines, one-half of the projection 131 of the strip 100 fits into the recess 14 of the strip 10, so that the crack between the side edge of the projection and the edge wall of the recess 14 does not register with the recess 15 formed between the tabs 11 and 111 but is to one side thereof. Hence, even if the strips were laid as shown in Fig. 2, with the tabs registering in the several rows, the fourth tab *a* 95 of the strip *b* of the upper horizontal row covers the dotted line *c* of separation between the upper body portions of the strips *d* and *e* of the strips of the lower row, and practically seals it against the entrance of water. Ordinarily the strips are laid with the recesses in one row, breaking joint with the recesses of the next adjacent rows.

Single shingles may be formed with the corresponding lateral projections and recesses as shown in Fig. 3. The shingle is shown at 20 and has the upper body portion 21 to be concealed or covered and the lower portion 22 to be exposed when the shingles are laid in overlapping horizontal rows.

The upper portion has on one side the lateral projection 23 and on the other side the recess 24. The difference in width between the projection and the recess is substantially equal to the space 25 between the lower exposed portions of two adjacent shingles.

By forming the elements as described, they may be said to interlock, to some extent, each previously laid element serving as a template to locate exactly the next laterally adjacent or contiguous element. The corner of one lateral projection fits in the reentrant angle formed by the recess in the next adjacent element.

15 The chief advantage residing in the construction which I have described is that, where two adjacent elements abut, the recess between the exposed portions thereof is closed at the upper end by the lower edge 20 of the projection 13, or 23, as the case may be, which extends laterally beyond the recess and prevents rain from being driven into the crack between the covered or concealed portions of said elements.

25 It is evident that the invention is not limited to the specific embodiment of the invention as herein illustrated and described, it being immaterial on which side of the element the projection is formed, so long as 30 the other side has a corresponding recess to receive it. In any case, the crack, between the sides of two adjacent elements at the upper portions thereof, does not open directly into the recess 13 or 25, as the case 35 may be, there being a shoulder extending across the line of said crack.

Having thus explained the nature of my said invention and described a way of making and using the same, although without 40 attempting to set forth all of the forms in which it may be made or all of the modes of its use, what I claim is:

1. A roofing element adapted with others to be laid in overlapping horizontal rows, 45 in simulation of a tiled or shingled roof,

comprising a body of which the upper portion is to be covered and the lower portion is to be exposed, when the same is laid, the upper portion having on one side a projection and on the other side a recess to receive 50 a like projection from the next laterally adjacent element, said projection being greater in width than said recess, whereby the exposed portions of two laterally adjacent elements are spaced apart, and said 55 projection extends across and forms the upper wall of such space.

2. A prepared flexible weatherproof roofing element adapted to be laid with others in overlapping rows in simulation of a tiled or shingled roof and consisting of a strip whose lower portion is formed with laterally spaced tabs, and whose upper portion has a projection on one side, and on the other side a recess to receive a like projection on an adjacent strip, the said projection being greater in width than said recess by an amount substantially equal to one of the spaces between said tabs.

3. A prepared weatherproof roofing element adapted to be laid with others in overlapping rows in simulation of a tiled or shingled roof and consisting of a strip of weatherproofed felt whose lower portion is formed with laterally spaced recesses and 75 tabs, and whose upper portion is formed at one side with a projection greater in width than the recess between said tabs and at the other side with a recess equal in width to one of said recesses to receive a like projection, 80 the said lower portion being of such width that, when two of said strips are laid side by side contiguously, a recess is formed between the two adjacent tabs thereof substantially equal in width to one of the first-mentioned 85 recesses.

In testimony whereof I have affixed my signature.

WILLIAM A. HARRIS.
